UNITED STATES PATENT OFFICE

162,704

TELEVISION CABINET

Samuel E. Adler, Chicago, Ill.

Application January 24, 1950, Serial No. 7,445

Term of patent 14 years

Cl. D56—4)

To all whom it may concern:

Be it known that I, Samuel E. Adler, a citizen of the United States, residing at Chicago, in the county of Cook, State of Illinois, have invented a new, original, and ornamental Design for a Television Cabinet, of which the following is a specification, reference being had to the accompanying drawings, forming part thereof.

Fig. 1 is a front perspective view of a television cabinet, showing my new design, the doors thereof being open;

Fig. 2 is an elevational view of the front of the cabinet, the doors being closed; and

Fig. 3 is an enlarged fragmentary vertical sectional view taken on line 3—3 of Fig. 2.

The dominant features of my design reside in that part shown in full lines in the drawing.

I claim:

The ornamental design for a television cabinet, as shown and described.

SAMUEL E. ADLER.
